UNITED STATES PATENT OFFICE.

FAY SAYRE, OF POND, CALIFORNIA.

WIRE-STRETCHER.

1,260,716.

Specification of Letters Patent. Patented Mar. 26, 1918.

Application filed November 6, 1917. Serial No. 200,579.

To all whom it may concern:

Be it known that I, FAY SAYRE, a citizen of the United States, residing at Pond, in the county of Kern and State of California, 5 have invented certain new and useful Improvements in Wire-Stretchers, of which the following is a specification.

This invention relates to wire stretchers and aims primarily to generally simplify 10 and improve the construction and operation of devices of this character, as well as to increase their efficiency.

A further object of the invention is to provide a wire stretching mechanism which is 15 capable of being quickly and easily applied to or removed from a fence post or other support, which is equipped with improved gripping means for securing wire strands to the stretcher frame and which is further 20 featured by improved means for moving the stretcher frame to properly tension the wire strand.

A further object of the invention is to provide a wire stretcher equipped with a 25 movable tensioning frame capable of being slid both ways in its support and operates so as to properly position the tensioned strand against the post or other support, thus facilitating the application of the tightened wire to its support.

Still further objects of the invention are to provide a wire stretcher which is of extremely simple and inexpensive construction, which may be adapted to posts of various 35 sizes, which develops a high degree of power with the expenditure of a relatively small amount of energy, which has its various parts so constructed and arranged as to minimize the opportunity for wear or break- 40 age, and which will prove highly practical and efficient in use.

In the drawings:—

Figure 1 is a side elevation of a stretching mechanism constructed in accordance 45 with the invention,

Fig. 2 is a top plan view of the improved stretcher mechanism,

Fig. 3 is an enlarged vertical sectional view taken through the body support of the 50 mechanism, and

Fig. 4 is a sectional view taken upon line 4—4 of Fig. 1.

Referring now more particularly to the drawings, 5 represents generally the supporting body of the improved stretching apparatus. This body is formed of an elongated metallic plate, bent intermediate its ends so as to provide a U-shaped structure, the parallel legs 6 of which are connected at their free ends by rollers 7. The legs 6 are 60 provided intermediate their ends with longitudinally extending notches 8, which rotatably support an axle 9 having a gear 10 affixed thereto, the said gear being disposed between the legs 6 of the U-shaped member. 65 The ends of the axle project beyond the body 5, and are squared as shown to receive a crank. Pivoted as at 11 within the U-shaped body and above the gear 10 is a pawl 12, and this pawl is normally held in engagement with the teeth of the gear 10 by a contractile spring 13. The pawl is equipped with an outwardly extending hand or finger grip 14, the latter protruding through an arcuate opening 16 in one of the legs 6 of 70 the supporting body. It is obvious, therefore, that when it is desired to withdraw the pawl 12 from engagement with the teeth of the gear 10, it is but necessary to move the hand or finger grip 14 rearwardly, and immediately upon releasing this finger grip, the spring 13 will force the pawl into engagement with the teeth of the gear.

Each of the legs 6 of the supporting body is provided midway its ends with a wire 85 clamping device indicated at 17. These wire clamps comprise plates hinged as at 18 to the exterior surface of the legs 6, and are held in clamping position by screw members 19.

Any preferred means may be used for holding the body support to a post; a chain 90 being employed in the present instance. This chain is firmly secured to one of the legs 6 of the supporting frame, and is provided at its outer end with a hook 21 adapted to engage with the opposite leg of the supporting frame.

Associated with the supporting body of the above mentioned type is a stretcher 100 frame represented at 22. This stretcher frame comprises a pair of heads 23 connected at one end by an elongated tubular member or pipe 24, and this tubular member is adapted to pass through the supporting body at the bight portion thereof. The heads 23 are connected at their opposite ends by a rack bar 25, which rests at its lower edge upon the rollers 7 connecting the free ends of the legs 6 of the supporting 105 body. This rack bar is engaged by the teeth of the gear 10 so that as the latter is

rotated, the rack bar will be moved inwardly or outwardly of the supporting body. The sides of the heads 23 are equipped with wire clamping members 26, identical with those arranged upon the opposing sides of the supporting body 5, and preferably in horizontal alinement therewith.

The frame 22 is provided with a spacing bar 28, which has its ends bent inwardly at right angles as at 29, and these ends are hinged to the outer faces of the heads 23 slightly below the upper ends thereof. This spacing bar is thus capable of being swung 10 from one side to the other of the frame and of the supporting body, and is engaged by rollers 31 rotatably mounted in suitable brackets upon the opposing sides of the body support 5. The spacing bar 28 is 15 adapted, when the device is in use, to rest against the side of the post, and by swingingly mounting the spacing bar upon the stretcher frame, it is obvious that the mechanism is rendered adaptable to either side 20 of the post. The spacing bar also assumes a share of the strain to which the supporting bar and stretcher frame are subjected 25 during the stretching operation.

To properly aline the wire strand being 30 stretched by the apparatus, a rod 35 is provided, the said rod having at one end an eye 36 in which one end of a chain 37 is secured. This rod is adapted to be inserted in either end of the hollow pipe 24, and the 35 chain 37 depending from the outer end of the said rod supports the wire strand indicated at 38 during the stretching operation.

In practice, the mechanism is applied to a post or other support by passing the chain 40 20 around the same. The gear 10 may be rotated so as to extend the stretcher frame beyond one side of the supporting body, and after the wire strand is clamped in the clamp members 26, the device is ready for 45 use. Rotation of the gear 10 in the proper direction will cause the frame 22 to move inwardly, drawing with it and properly tensioning the wire strand 38. Should one of such operations be insufficient to properly 50 tension the wire, the strand end may be clamped in one of the grips 17 on the body support while the frame is being again extended, whereupon the clamps 26 are again gripped upon the wire. It will be 55 observed, particularly with reference to Fig. 2 of the drawings, that the strand is brought relatively close to the post which supports the apparatus so that the said strand may be quickly and easily nailed to the said post. 60 By arranging the grip members 17-26 in

horizontal alinement, twisting, bending and breaking of the wire strand is obviated.

From the foregoing it is obvious that I have provided a stretching mechanism which is of extremely simple construction 65 and which may be quickly and easily applied to a fence post. Should it be desired to stretch a fence fabric, a suitable clamping mechanism might be secured to either end of the slideable frame. 70

While the present is a disclosure of what is believed to be the preferred embodiment of the invention, it is to be understood that the invention is not limited thereto, but that various changes in the minor details of construction, proportion, and arrangement of parts may be resorted to if desired, without departing from the spirit of the invention as defined in the appended claims. 75

I claim:—

1. In a wire stretcher, a supporting body adapted to be attached to a post, a frame 80 slidably mounted in said body, a bar extending longitudinally of said frame and being adapted to engage said post, a roller 85 on said supporting body to engage said bar, a clamp on said frame, and means on said body for sliding said frame.

2. In a wire stretcher, a body, a frame 90 slidably arranged in said body, a hollow member extending longitudinally of said frame, a rod adapted to be inserted in either end of said hollow member, a chain carried by said rod, a grip member on said frame, and means for sliding said frame. 95

3. In a wire stretcher, a body, a frame 100 slidably arranged in said body, a pair of wire clamps carried by said body and being arranged one on each side thereof, a pair of clamps on each end of said frame and being disposed on each side thereof, and 105 in alinement with the clamps on said body, and means for sliding said frame.

4. In a wire stretcher, a body, a frame 110 slidably carried by said body, a bar having its ends bent at right angles to the main portion thereof, the said angularly bent ends being hingedly connected to the ends of said frame, a pair of rollers arranged one on each side of said body and being 115 adapted to support said bar, wire gripping means on said frame, and means for moving said frame within said body.

In testimony whereof I affix my signature in presence of two witnesses.

FAY SAYRE.
